UNITED STATES PATENT OFFICE.

ROBERT G. CAMBLIN, OF BARTLESVILLE, OKLAHOMA, ASSIGNOR OF ONE-HALF TO
TULLIE E. MILLER, OF KAW CITY, OKLAHOMA.

HEADLIGHT-CONTROLLING MEANS.

Application filed September 1, 1923. Serial No. 660,553.

To all whom it may concern:

Be it known that I, ROBERT G. CAMBLIN, a citizen of the United States, residing at Bartlesville, in the county of Washington and State of Oklahoma, have invented certain new and useful improvements in Headlight-Controlling Means, of which the following is a specification, reference being had to the accompanying drawings.

10 This invention relates to headlights, and more particularly to those headlights wherein the reflectors are dirigible for the purpose of causing the direction of the beams of light proceeding from said reflectors to be directed in different directions.

The general object of the present invention is to do away with the necessity of using dimmers or like devices on headlights, as is commonly done. It has been proposed 20 to provide means whereby a headlight may be turned downward or whereby the light may be directed downward, but this, while it avoids dazzling of an oncoming driver, does not illuminate the road on the right 25 hand side, and an object of the present invention is to provide a construction of the character described wherein a beam of light, upon actuation of the device by the driver, will be shifted from a direction 30 parallel to the line of travel to a direction toward the right to thus prevent blinding of the oncoming driver and at the same time cast the light toward the ditched side of the road.

35 A further object is to provide a construction of this character wherein the headlight reflectors are hingedly mounted within the ordinary or usual headlight housing, the headlight reflectors being hinged on the left 40 hand side of both housings, and manually operable means being provided for urging both reflectors into a position where their axes are parallel to the axes of the headlight housings and the longitudinal axis of the 45 car, and manually controlled means for shifting the reflectors laterally upon their hinges so that the light will be directed toward the right.

50 A still further object is to provide manually controlled, motor operated means for shifting these reflectors.

Other objects will appear in the course of the following description.

55 My invention is illustrated in the accompanying drawings, wherein:—

Figure 1 is a fragmentary top plan view of an automobile showing my attachment applied thereto;

Figure 2 is a horizontal section of one of the headlights;

Figure 3 is a horizontal section as in Figure 2, but showing the reflector shifted;

Figure 4 is a section on the line 4—4 of Figure 2;

Figure 5 is a fragmentary section on the line 5—5 of Figure 1;

Figure 6 is a vertical section of the dash board, showing the operating device thereon;

Figure 7 is an enlarged sectional view 70 through the radiator D, showing the manner in which the housing for the cable 29 is mounted in the radiator;

In the drawings, I have illustrated diagrammatically the forward end of an 75 ordinary motor car having the usual hood A and the dirigible wheels B and the dash board C. Supported upon the fenders of the motor car or in any other suitable manner are the headlight housings 10. Inasmuch as both of these housings are alike 80 and both the reflectors in the housings are alike, the same numerals will be used for both headlights.

Each headlight housing 10 in plan view 85 is approximately parabolic and is provided with the concavo-convex lens 11, or pane supported by a rim 12 having interlocked engagement with the rim of the headlight housing, as at 13. Hingedly mounted 90 within the headlight housing 10 is the reflector 14, this being hinged in any suitable manner, as at 15, to the left hand side of the housing. The reflector 14 carries the usual lamp socket 16 supporting the usual 95 electric lamp 17. The wiring of this lamp is of any ordinary or suitable character.

Attached to the parabolic reflector 14 adjacent its rear end is a rearwardly and laterally directed arm 18 which passes 100 through a slot in the housing and which has a knuckle at its extremity which is connected to a transverse rod 19 formed in two sections, the sections having screw-threaded engagement with each other, as at 20, and 105 the sections being held in adjusted position by the jam nut 21. This connecting rod 19 is pivotally connected by a knuckle joint to the arm 18 of the opposite reflector, as illustrated in Figure 1.

A spring 22 is connected to the inner face of the lamp housing and at its other end is connected to this arm 18 and acts to draw the arm 18 toward the right. The 5 arm 18 has a screw-threaded bore and engaging this bore is an adjustable stop 23 held in place by a jam nut 24, and this adjustable stop is adapted to engage with an abutment 25 formed on the interior face 10 of the lamp housing, as shown in Figure 3.

Adjacent the free edge of the lamp housing, that is at a point nearly diametrically opposite the hinge 15, is an arm 26. This 15 arm passes through a slot 27 in the lamp housing and is pivotally connected to a coupling 28, in turn connected to a flexible cable 29. This cable extends rearward to an actuating device, as will hereafter be described, and by its means the lamp may 20 be swung against the action of the spring 22 to position in Figure 3.

For the purpose of preventing any rattling of the reflector, I mount upon the rim 12 a stop 30 having therein a groove or recess 31 which is V-shaped in cross section and which is lined with rubber packing 32, and I form the edge of the lamp housing with an outwardly projecting V-shaped lug 33 adapted to engage in said recess to thus 30 hold the reflector and hold its free end when the reflector is forced forward by the spring 22.

The rear end of the cable 29 passes around or over a spool 34 mounted within the hood 35 B at the dash board or in a like situation. This spool is mounted upon a shaft, in turn geared to or otherwise operated by a small electric motor or equivalent device 35. Obviously when the motor is actuated the cable 40 29 will be wound up and this will shift both lamp housings to a position where the stop pin 23 engages with the stop abutments 25. When the current is turned off the motor, the springs 22 will draw the lamp housings back to their normal positions. Any 45 suitable switch on the instrument board may be used for controlling the operation of the motor.

In case the battery should be weak, the 50 wiring defective, or some other accident happen which would prevent the use of this motor, I may also carry the cable 29 around the spool 34, then up over a pulley 36, through the dash board or instrument board, to a lever 37 which may be pulled by the 55 operator to thus shift the reflectors. This lever operates in a slot through a bracket 38 or like device. In either case it will be obvious that a strain placed upon the cable 60 29 will cause the oscillation of the lamps to the right and the casting of the light to the right and that a release of the strain on this cable will permit the springs 22 to shift the reflectors to their initial positions. 65 Preferably the lamp housing will be provided

with a small hood 39 over the slots for the passage of the arms 18 and 26 so that no rain will enter these slots.

In the use of this device, when two cars meet each other the operator simply operates the motor 35 or the handle 37 and thus places a strain upon the cable 29 and the reflectors are drawn over so that the light is thrown toward the right and into the right hand ditch, thus out of the approaching motorist's 75 eyes, while at the same time illuminating the ditch. As soon as the emergency has passed, the operator releases the handle 37 or the switch controlling the motor and the springs 22 then draw the lamp housings back 80 to their initial positions with the light-rays thrown ahead in the usual manner.

The cable 29 preferably passes through a tubular housing 40 which is disposed within the engine hood and through the radiator 85 casing and extends nearly to the drum or spool 34. This tubular housing 40, as illustrated in Figure 7, passes through the radiator and is supported on the radiator by making the tube 40 with a shoulder 41 90 against which a leather or rubber washer 42 bears. The remainder of the tube is screw-threaded, as shown at 43, and carries a nut 44 and between the nut and the radiator there is disposed a leather or rubber washer 95 45. The purpose of this housing is to prevent the flexible cable 29 from being cut or damaged and also prevent the radiator from being damaged by friction with the cable. 100 Also in case the cable should break this prevents the cable from being tangled up in the fan, generator, magneto, pump shaft or other parts of the motor and thus doing serious damage. Preferably a small tip of rubber or other like material 46 will be disposed on 105 the stop 25.

It is obvious that other forms of lamp than the parabolic lamp, illustrated may be used, such as the ordinary "drum-shaped" lamp quite commonly found on machines. 110 It will also be understood that dimmers should be used in connection with the lamps, as these dimmers are required for city driving. Obviously the use or non-use of dimmers does not affect my invention at all. 115

It will be seen that this construction is very simple, thoroughly effective for the purpose intended, and involves no dirigible mounting of the housing itself. I do not wish to be limited to the details of construction and arrangement of parts as illustrated, as it is obvious that many changes might be made therein without departing from the spirit of the invention as defined in the appended claim. 125

I claim:—

The combination with a vehicle, of a pair of headlight housings rigidly mounted on the vehicle with their axes parallel to the longitudinal axis of the vehicle, a reflector 130

mounted in the housing for oscillation and carrying a lamp, means for oscillating the reflectors including arms extending from the reflectors through the housings, a connecting rod connecting said arms whereby the reflectors shall have simultaneous movement in the same direction, an arm extending from one of said reflectors and through the housing thereof, a cable connected to the

arm, an electric motor operatively engaged with the cable whereby when the motor is actuated the cable shall be retracted, a stop limiting the retractile movement of the reflector, and a spring urging the reflector to its normal position.

In testimony whereof I hereunto affix my signature.

ROBERT G. CAMBLIN.
